UNITED STATES PATENT OFFICE

2,434,962

ELECTRON DISCHARGE DEVICE OF THE
CAVITY RESONATOR TYPE

Ernest Rostas, Lyon, France, assignor to International Standard Electric Corporation, New York, N. Y., a corporation of Delaware

Application June 3, 1943, Serial No. 489,473
In France May 17, 1940Section 1, Public Law 690, August 8, 1946
Patent expires May 17, 1960

7 Claims. (Cl. 250—27.5)

1

The present invention relates to electron discharge devices and more particularly to designs for those devices of this kind that use modulation of the velocity of the electrons.

According to certain of its characteristic features the present invention provides for velocity modulation devices of concentric design comprising at least one resonant cavity having axial symmetry of revolution and being permeable to the electrons and coaxial to the emission cathode, so that the entire beam of electrons passes perpendicularly to the axis of revolution of the cavity. When use is made of a single cavity resonator in a concentric structure of this kind, a coaxial electrode for reflecting the electrons is provided around the said cavity resonator. When use is made of two cavity type resonators in the path of the beam, the electrode that surrounds the outer cavity is simply an electron collector.

Among other advantages, concentric electrode structures of this kind have that of reducing the current density of the beam for the same transported current with respect to the units in which the electronic flow is concentrated in an elongated beam projected along a path, and also that of making it easier to obtain a beam suited to the design, since the concentration of a flow of electrons between two planes is easier to effect than that of a flow of electrons in pencil form.

Fig. 1 shows in elevation, and partly in section one example of a type of construction that embodies characteristic features of the invention;

Fig. 2 is a sectional view taken along 2—2 of Fig. 1;

Fig. 3 is a section on a larger scale taken along 3—3 of Fig. 1; and

Fig. 4 illustrates a modified portion of the unit shown in Fig. 1.

The devices shown in Fig. 1 comprises within an evacuated envelope 1, e. g. of glass, a cathode 2 of elongated cylindrical shape, a cylindrical electrode 3 coaxial with cathode 2 and serving to reflect or return the electrons emitted by cathode 2 that reach its vicinity, and an electrode 4 that is permeable to the electrons and is disposed between cathode 2 and the reflecting electrode 3 and coaxially with these electrodes.

The entire unit is supported from a reentrant stem 5 of the insulating envelope 1 by means of supporting rods 6, three in the example shown, as can be seen in Fig. 2. These supporting rods are carried by the reentrant stem 5 by means of collars 7 which may be in several parts, e. g. three, and which are secured on the stem 5, by bolts as shown at 8 that connect these parts to

2

each other. Current or potential lead-in connections 9 to the various electrodes pass through the stem 5, and are sealed hermetically therein.

The supporting rods 6 are secured to a circular metallic plate 10 which they traverse in the manner shown at 11 and their upper ends pass through openings 12 in another metallic plate 13 in such a way as to center this plate 13 without being secured to it. Each of the metallic plates 10 and 13 has a diameter almost equal to that of the envelope and carries stops or short upturned rods 14 which thus maintain two insulating sheets 15 and 16, e. g. of mica, spaced from the metallic plates 10 and 13 that support them. These mica sheets may have the shape shown in Fig. 2. On the one hand they insure centering of the cathode 2 and, on the other hand, they serve, as shown at 17, for supporting the conductive uprights 18 on which the reflecting electrode 3 is soldered.

Cathode 2 is shown as an indirect heated cathode with only a central portion 19 coated with electron emitting material. This active portion 19 cooperates with the permeable electrode 4. As shown in the drawing, this permeable electrode consists of two coaxial metallic sleeves 23—24 and 25—26 maintained in spaced relation by conductive spacing members 27—28 in such a way as to form an annular cavity resonator, the walls of 30 which are completed as regards the active portion 19 of cathode 2 by a grid that consists of two spaced layers of wires or rods 20 and 21 which are curved toward the outside of the unit and are set in notches in the walls of the cavity resonator 35 like those shown at 22 in Fig. 3. This electrode unit 4 is secured coaxially with cathode 2 on the metallic plates 10 and 13.

In the operation of the above described type of construction, the electrode with a resonant annular cavity is brought to a positive potential with respect to cathode 2, and the reflecting plate 3 is brought to a negative potential with respect to that of the electrode 4 and to substantially the same or a negative potential with respect to that of cathode 2, so that the flow of electrons coming from the emissive portion 19 of the cathode passes through the permeable electrode 4 on its way to electrode 3 and, during its passage through the annular resonant cavity, it undergoes a grouping in velocity that insures a modulation in velocity of the beam while it is on its way to electrode 3 and returns to electrode 4 after reflection. On its passage back to electrode 4 it yields a part of its energy to the cavity resonator. This kind of operation is well known and

will consequently not be described in further detail. The output energy is collected on the concentric resonator electrode, e. g. in the manner shown in Fig. 1, by means of a transmission line that has each wire 29 and 30 respectively connected to one of the walls of the cavity resonator and that passes through a seal 31 in the insulating envelope 1. As mentioned, the portion of each wire 29 or 30 that is within the envelope 10 may be flexible in order to permit free expansion of the complete unit during operation.

Fig. 4 illustrates a structure with concentric elements of the above described type but in which the cavity resonator is double, the beam not being returned but being picked up by electrode 3 15 which is then brought to a positive potential with respect to cathode 1 and electrode 4. In this case, this latter electrode consists of two adjoining cavity type resonators 32 and 33. The grid portions of these cavities may be constructed in the manner described for Fig. 1, i. e. they may consist of rods bent outwardly, such as 34 and 35, which are set in notches of coaxial cylindrical sleeves 36, 37 and 38, the sleeve 37 having two parallel annular rims 39 which define a toroidal space in which those electrons can freely move which have undergone a grouping in velocity on their passage through grids 35 and are on their way to grids 36. From the beam modulated in this way that passes through them, the grids 36 draw energy in a manner likewise known in devices with modulation of the velocity of the electrons.

It can be seen that a concentric arrangement of the electrodes of a velocity modulation device is more suitable than other plane structures for obtaining a beam of electrons that can pass through the permeable portions of an oscillatory circuit without being picked up by the walls as a result of the reduced density of the beam for the same transported electron current.

Although the invention has been described for the case of certain special examples of embodiment, it is evident that it is by no means limited thereto; but is on the contrary capable of numerous modifications and adaptations without departing from the scope thereof.

What is claimed is:

1. An ultra high frequency electron velocity modulation device including an electron-emitting cathode for developing radial streams of electrons, means for modulating the velocity of the electrons in the path of said stream and transferring energy therefrom to an oscillating field, the last-mentioned means comprising a substantially cylindrical cavity resonator having two spaced walls concentrically surrounding said cathode, aligned windows in each of said walls for defining said path of the stream as an annular electron path for the electrons from said cathode, electron repeller means surrounding said aligned windows, and grid electrodes mounted in each of said aligned windows, each of said grid electrodes being bowed outwardly along said path of the electron stream from the cathode thereby defining a substantially toroidal space between said grids.

2. An ultra high frequency electron velocity modulation discharge device including an electron-emitting cathode for developing a radial stream of electrons, a first cylindrical cavity resonator surrounding and concentric with said cathode, a second cylindrical cavity resonator surrounding and concentric with the said first

cavity resonator, a pair of grids attached respectively to radially aligned windows in the walls of said first resonator for controlling the velocity modulation of electron streams therebetween, 5 each of said grids being bowed outwardly along the path of the electron stream from the cathode thereby defining a substantially toroidal space extending across said path of the electron stream; a second pair of grids attached respectively to radially aligned windows in said second resonator thereby defining a second substantially toroidal space in radial alignment with the first-mentioned toroidal space, and a common electron velocity control electrode surrounding and in radial spaced relation to said second resonator and in substantial alignment with said grids.

3. An ultra high frequency electron velocity modulation discharge device according to claim 2, wherein said first and second resonators are separated by a common intervening conductive wall member, the outermost grid of the said first pair of grids defining with the innermost grid of the said second pair of grids a localized electron transmission chamber between the two cavity resonators which chamber extends through said common wall and is electrically connected therewith.

4. An ultra high frequency electron velocity modulation device comprising an electron-emitting cathode for developing a radial electron stream, a cavity resonator including two cylindrical spaced walls surrounding and concentric with said cathode, each of said walls having aligned windows in which are located annular grid structures, each grid being bowed outwardly with respect to the path of the electron stream from the cathode thereby defining a substantially toroidal electron chamber between the grids, and an electron repeller electrode surrounding said grids in spaced relation thereto and in substantial alignment therewith.

5. A device according to claim 4 in which said grids are located substantially at the central portion of said cylindrical walls, and said repeller electrode is mounted in substantial alignment with said central portion, and lead-in means is connected to said repeller electrode for applying thereto an electron repelling potential.

6. A device according to claim 4 in which each of said grids comprises a series of rod-like elements extending along the length of the cathode and with the ends of the rods fastened to the said cylindrical walls at the margins of the respective window therein.

7. An ultra high frequency electron velocity modulation tube comprising a central elongated substantially linear cathode member having its middle peripheral region provided with an electron-emissive coating, a first cylindrical member surrounding said cathode, a second cylindrical member surrounding the first cylindrical member and constituting therewith a cavity resonator, each of said cylindrical members having the middle peripheral section thereof provided with a gridded window which windows are in substantial alignment with the said coated area of the cathode, and with the grid members bowed outwardly in the direction of the electron trajectories from said cathode, another cylindrical electrode surrounding the outer one of said cylindrical members in spaced relation thereto and in substantial alignment with said gridded windows, and means supporting all said electrodes 70 in fixed concentric relation including upper and

lower electrode spacer discs between which the electrodes are mounted.
